CLAIM

The ornamental design for a combined air conditioner, as shown and described.

DESCRIPTION

FIG. 1 is a left side view of the combined air conditioner;
FIG. 2 is a front side view of the combined air conditioner;
FIG. 3 is a right side view of the combined air conditioner;
FIG. 4 is a rear side view of the combined air conditioner;
FIG. 5 is a top side view of the combined air conditioner;
FIG. 6 is a left side view of the part A of the combined air conditioner;

FIG. 7 is the front side view of the part A of the combined air conditioner;

FIG. 8 is a right side view of the part A of the combined air conditioner;

FIG. 9 is a rear side view of the part A of the combined air conditioner;

FIG. 10 is a top side view of the part A of the combined air conditioner;

FIG. 11 is a left side view of the part B of the combined air conditioner;

FIG. 12 is a front side view of the part B of the combined air conditioner;

FIG. 13 is a right side view of the part B of the combined air conditioner;

FIG. 14 is a rear side view of the part B of the combined air conditioner;

FIG. 15 is a top side view of the part B of the combined air conditioner;

FIG. 16 is a perspective view of the combined air conditioner; and,

FIG. 17 is a perspective view of the combined air conditioner in which the part A and part B are located separately.
